DESIGN FOR A GOLF PRACTICE GAME DEVICE

John T. Berdner and Gerald C. Fennell, San
Francisco, and Raymond O. Wilson, Los Altos,
Calif.

Application June 30, 1939, Serial No. 85,780

Term of patent 7 years

To all whom it may concern:

Be it known that we, John T. Berdner, Gerald C. Fennell, and Raymond O. Wilson, citizens of the United States, residing in the cities of San Francisco, San Francisco, and Los Altos, respectively, counties of San Francisco, San Francisco, and Santa Clara, respectively, State of California, have invented a new, original, and ornamental Design for a Golf Practice Game Device, of which the following is a specification, reference being had to the accompanying drawing, forming part thereof.

The figure is a perspective view of a golf practice game device, showing our new design. The opposite side of the article is of substantially the same configuration and appearance as the side shown.

We claim:

The ornamental design for a golf practice game device, as shown and described.
